CLAIM

The ornamental design for a gauge pod, as shown and described.

DESCRIPTION

FIG. 1 is a front view of a gauge pod, in accordance with the present invention;

FIG. 2 is a rear view of the gauge pod shown in FIG. 1;

FIG. 3 is a left side view of the gauge pod shown in FIG. 1;

FIG. 4 is a right side view of the gauge pod shown in FIG. 1;

FIG. 5 is a top view of the gauge pod shown in FIG. 1;

FIG. 6 is a bottom view of the gauge pod shown in FIG. 1; and,

FIG. 7 is a perspective view of the gauge pod shown in FIG. 1, viewed from above and to the right front of the gauge pod; and,

FIG. 8 is a perspective view of the gauge shown in FIG. 1, viewed from below and to the left rear of the gauge pod.
